CLAIM

The ornamental design for bicycle headlamp, as shown and described.

DESCRIPTION

FIG. 1 is a right side elevation view of a bicycle headlamp showing our new design;

FIG. 2 is a rear elevation view thereof;

FIG. 3 is a front elevation view thereof;

FIG. 4 is a top plan view thereof, the depicted switch being displaceable through at least two positions including the left position shown;

FIG. 5 is a bottom plan view thereof; and

FIG. 6 is a top, left rear perspective view thereof.

*FIG. 1.**FIG. 2.**FIG. 3.**FIG. 4.*

FIG. 6.

FIG. 5.
